Patented Oct. 30, 1917.

Inventor

William A. Trost.

By Henry L. Reynolds, Attorney.

UNITED STATES PATENT OFFICE.

WILLIAM A. TROST, OF SEATTLE, WASHINGTON.

DOLL.

1,244,799.

Specification of Letters Patent. Patented Oct. 30, 1917.

Application filed October 11, 1916. Serial No. 124,963.

To all whom it may concern:

Be it known that I, WILLIAM A. TROST, a citizen of the United States, and resident of the city of Seattle, county of King, and 5 State of Washington, have invented certain new and useful Improvements in Dolls, of which the following is a specification.

My invention relates to dolls, and consists of an improvement whereby the doll's 10 eyes may be made to close gradually, thus imitating the actions of a child while going to sleep.

An object of my invention is to produce a device of the above character which is 15 simple and compact in construction, and which will operate to gradually close the eyes of the doll. Another object is to produce lost motion in such a device, whereby the doll's eyes will not close immediately 20 upon rocking the doll, but their closing will be delayed until the doll has been rocked for a period.

My invention consists of the novel parts and combinations of parts which are shown 25 in the accompanying drawings, and which will be hereinafter described in the specification and defined by the claims terminating the same.

In the drawings I have shown my invention embodied in forms which are now preferred by me.

Figure 1 is a section through the doll's head, showing in full lines the parts in the position they would assume when the doll 35 is in the upright position.

Fig. 2 is a similar section of a slightly modified form.

Fig. 3 is a section through the escapement rack, showing the weighted carriage.

Fig. 4 is a bottom plan view of a portion of the escapement rack.

When a child is being rocked to sleep, it does not close its eyes as soon as the rocking commences, nor does it close them quickly.

45 After a period of rocking the child's eyes gradually close, and soon he is asleep. This action is closely imitated by my invention.

In the ordinary type of sleeping doll the eyes close as soon as the doll starts to assume a recumbent position. My device provides a mechanism which automatically

keeps the eyes open when the doll is lying down, and which, after a period of rocking, begins gradually to close the eyes, and continues the eye-closing movement while the 55 rocking continues. When the doll is raised to an upright position, the eyes immediately open, and the same rocking must be gone through with to close them again.

The eyes 1 are pivoted in the head 2 in 60 the usual manner, or in any other suitable manner. A bar 11 joins the two eyes within the head. A rod 12 projects from the bar 11, and is secured therein to open and close 65 the eyes. The rod 12 is preferably forked near its connection with the bar 11.

Within the head, and slanting, preferably from the rear edge of the upper opening to the chin, is secured an escapement rack bar 3. Upon opposite sides of this rack are teeth 70 31, arranged in staggered relation, as shown in Fig. 4. The number of teeth is immaterial, but the more teeth there are on the bar 3, the more rocking is necessary to close the eyes. 75

The upper edge 32 of the bar 3 serves as a track upon which may slide a weighted carriage 4. If desired a roller 41 may be journaled at the upper edge of the carriage to run upon the edge 32. The weight 42 is 80 preferably secured to both sides of the carriage beneath the rack 3, in order to prevent the displacement of the carriage.

Upon the carriage 4, and adapted to engage the teeth 31 when the doll is in recumbent position, are a pair of opposed escapement teeth 43. When the doll is in upright position these teeth 43 are thrown out of engagement with the teeth 31, due to the action of gravity upon the weight 42. The 90 upright position of the doll is shown in Figs. 1 and 2, in which the full lines represent the parts in the position they would occupy at such a time, and the dotted lines show the position of the parts at the end 95 of their motion, after placing the doll in recumbent position. A pair of ears 44, provided with holes 45, project from the carriage 4.

A link 5 is pivoted in the free end of the 100 rod 12, and has one end passing through the holes 45. At the free end of the link

is a knob 51 which engages with the ear 44, and a similar knob 52 engages the ears at the other end of the link. In Fig. 2 the parts are reversed, so that the knob 51 comes at the inner end of the link 5. This transforms the action of the carriage 4 from a pull upon the eyes to a push.

The operation of the device will be apparent from the foregoing description.

- 10 When the doll is laid down, the teeth 43 engage the rack teeth 31, and the motion of the carriage down the bar is arrested. When the doll is rocked, the sidewise motion rocks the carriage 4, which is loosely mounted upon the bar 3, and the teeth 43 escape, first on one side and then on the other. There is sufficient friction in the eye sockets to keep the eyes open.

As the carriage travels down the track 32 there is at first no motion of the eyes, though the carriage slowly travels down the track. When the knob 51 engages the ears 44, the motion of the carriage exerts a pull upon the eyes, and gradually closes them. When 25 the doll is raised upright, however, the teeth 43 swing upward and are disengaged from the rack teeth 31. The carriage then slides down the track 32, and as soon as the ears 44 engage the knob 52, the eyes are opened.

30 What I claim as my invention is:

1. The combination with a doll's head having eyes movable into open and closed position, of an eye opening and closing mechanism comprising a weight actuatingly connected to the eye, said weight tending to move by gravity to close the eyes when the doll is in recumbent position, and means permitting said motion only while the weight is being laterally reciprocated.

40 2. The combination with a doll's head having eyes movable into open and closed position, of an eye opening and closing mechanism comprising a weight actuatingly connected to the eye, said weight tending to move by gravity to close the eyes when the doll is in recumbent position, and to open the eyes when the doll is in upright position, and positively-acting means permitting said closing motion only while the 50 weight is swung from side to side.

3. The combination with a doll's head having eyes movable into open and closed position, of an eye opening and closing mechanism comprising a weight actuatingly connected to the eye, said weight tending to move by gravity to close the eyes when the doll is in recumbent position, positively-acting means permitting said motion only while the weight is being swung from side to side and means for producing lost motion in the 60 closing mechanism.

4. The combination with a doll's head having eyes movable into open and closed

position, of a weight actuatingly connected to the eyes and movable by gravity to close the eyes, means for regulating the speed of closure of the eyes, comprising a detent for the weight, said weight being movable against said detent only while being swung from side to side, and means for delaying the closing action of the weight upon the eyes.

5. The combination with a doll's head having eyes movable into open and closed position, of an escapement mounted within the head, said escapement comprising a fixed member and a movable member co-operating therewith to operate the eyes, and movable by gravity upon said fixed member only when the doll is rocked from side to side, thereby delaying the closing of the eyes.

6. The combination with a doll's head having eyes movable into open and closed position, of an escapement comprising a fixed member and a movable member adapted to act by the force of gravity upon said fixed member, and operable by agitation of the doll, actuating connection between the eyes and said movable member whereby motion of the movable member may act to close the eyes gradually, and means for producing lost motion in said escapement to delay the beginning of the eye-closing movement.

7. The combination with a doll's head having eyes movable into open and closed position, of an escapement rack mounted within the head, a weight movable lengthwise of said rack, actuating connection between said weight and the eyes, and teeth upon said weight engageable with said rack when the doll is in recumbent position, and disengageable therefrom when the doll is upright.

8. The combination with a doll's head having eyes movable into open and closed position, of an escapement rack mounted within the head, a weight movable lengthwise of said rack, an ear upon said weight having an aperture therein, a rod secured in the eyes to turn them, a link pivoted to said rod and passing through said aperture in the ears, and adapted to be engaged by the ears to form an actuating connection between the weight and the eyes, and teeth upon said weight engageable with said rack when the doll is in recumbent position and disengageable therefrom when the doll is upright.

9. The combination with a doll's head having eyes movable into open and closed position, of an escapement rack mounted within the head, a weight movable lengthwise of said rack, an ear upon said weight having an aperture therein, a rod secured in the eyes to turn them, a link pivoted to said

rod and passing through said aperture in the ears, a knob upon one end of said link adapted to engage said ears to form an actuating connection between the weight and 5 the eyes, and teeth upon said weight engageable with said rack when the doll is in recumbent position, and disengageable there-

from when the doll is upright, the weight being adapted to move by gravity along the rack when the doll is agitated while in recumbent position. 10

Signed at the city, county and State of New York, this 29 day of September, 1916.

WILLIAM A. TROST.
